APPARATUS FOR SURFACING RAILWAY JOURNAL BOX WEDGES

Application filed February 12, 1929. Serial No. 339,302.

This invention relates to apparatus for surfacing railway journal box wedges and is particularly useful in resurfacing such wedges when they become worn from use.

5 The primary object of the invention is the provision of means which are simple in construction and operation for effectively and economically surfacing or resurfacing journal box wedges.

10 The nature, objects and advantages will appear more clearly from a consideration of the following description considered in connection with the accompanying drawings which illustrate a preferred embodiment of the apparatus and in which

Fig. 1 is a side elevation of the apparatus employed;

20 Fig. 2 is a front view of the same, certain portions of the supporting structure being omitted;

Fig. 3 is a view taken substantially as indicated by the line 3—3 of Fig. 1; and

25 Fig. 4 is a side view of a journal box, a portion of which is broken away to show the journal bearing and its backing or wedge member therein.

Referring now to the drawings it will be seen that the apparatus of the present invention includes a suitable upright supporting structure 5 and a work table 6 mounted for vertical movement at one side of the structure 5, the said table being vertically adjustable by means of the jack screw device 7 which may be manually operated by means of the hand wheel 8 (see Fig. 2).

30 A second work table 9 is mounted for movement toward or away from the upright supporting structure 5, the said table 9 being carried on the table 6 and being provided with manually operable means 10 of a well known construction for effecting its movement. A third work table or support 11 is supported on the table 9 and arranged for transverse movement with respect thereto. The movement of this third table 11 is carried on automatically by means of an operating connection with the motor 12 which is mounted at the top of the supporting structure 5. The operating connection includes a sprocket and chain coupling 13 (see Fig. 3) between the

motor shaft 14 and the shaft 15 which is suitably mounted in parallel relation to the motor shaft 14. The shaft 15 carries a gear 16 (see Fig. 1) which meshes with a gear 17 secured to a third shaft 18, the shaft 18 also being mounted in parallel relation to the motor shaft 14. A shaft 19 is arranged at right angles to the shafts 14, 15 and 18 and carries a worm wheel 20 which meshes with a cooperating worm 21 secured to the shaft 18. The shaft 19 carries a gear 22 which, in turn, meshes with a gear 23 mounted on the shaft 24, the latter being arranged at right angles to the shaft 19 and parallel to the shafts 14, 15 and 18. It should be noted that the shaft 24 is mounted in a suitable open frame work or box 25 carried on the supporting structure 5 and that the gear 23 is splined on the shaft 24, the latter being provided with a suitable key way 26 which engages the key 56 mentioned in one of the extended hubs 27 in order to permit longitudinal movement of the shaft 24 thru the structure 25. Suitable bearings 54 are mounted on the hubs 27 on each side of the gear 23 and collars 55 secured in the box-like structure 25 are mounted on the hubs and engage the bearings 54 in order to retain the gear 23 in position to mesh with the gear 22.

35 A support or bearing 28 for the shaft 24 is mounted on the table 9 by means of the bracket member or arm 29. A pair of universal joints 30 are provided in the shaft 24 between the bearing 28 and the box-like supporting structure 25. The end of the shaft 24 adjacent to the work tables is provided with a crank arm 31 which is operatively connected with the uppermost table 11 by means of the connecting link 32. Thus when the motor 12 is in operation the table 11 is reciprocated across the table 9.

40 The motor shaft 14 carries a suitable grinding wheel 33 above the table 11 on which is adapted to be mounted the wedge holder member 34. It should be observed that the body of the holder member is secured to the table 11 and that the same is provided with upright sides or flanges 35 between which the wedge W to be ground is mounted and secured, suitable bolts 36 being provided in the side members 35 for

this purpose. It should also be noted that the upper edges of the members 35 are curved to conform to the contour of the desired upper surface of the wedge W.

5 At this point it should be observed that the motor 12 is mounted on a supporting member 37 (see Fig. 3), the said member 37 in turn being mounted for vertical movement in the upper portion of the supporting structure 5 which, as is indicated in Fig. 3, takes the form of an open box-like structure 38 which cooperates with the member 37 to guide the same in its vertical movement. The support 37 is provided with two dependent lugs 39 which are spaced apart a sufficient distance to engage the curved member or master radius 40. The member 40 is arcuate in formation and has the same curve as that desired to be produced on the upper surface of the wedge member W. A roller 41 is mounted between the lugs 39 in position to ride on the upper surface of the member 40 and a pair of rollers 42 are secured to the lugs 39 at their lower extremities in position to be engaged by and travel through the grooves 43 in the edges of the member 40, the grooves being curved similarly to the upper surface of the member 40. The member 40 is mounted on and secured to a carrier member 44 which extends through suitable apertures in the front and back walls of the box-like structure 38. Grooved guides or channel members 57 are provided for supporting and guiding the carrier 44 and wear gibs 58 are preferably arranged at the lower flange of the guides 57. A connection member 45 is provided between the member 44 and the table 9. The connection 45 is secured to the table 9 by means of the bolt 46 passing through a suitable vertically extending slot-like aperture in the angled end 47 of the member 45.

In considering the operation of the invention, reference should first be made to Fig. 4 in which we have illustrated a railway journal box 48 adapted to house a journal 49. The weight of the railway vehicle is transmitted to the journal 49 through the top of the box 50, the bearing wedge or backing member W and the bearing brass 52. It should be understood at this point that the upper surface 53 of the wedge is rounded or curved longitudinally of the journal 49 in order to permit a rocking of the top 50 of the box on the wedge when the wheels of the vehicle encounter irregularities in the track. It should also be observed that this form of construction is substantially standard at the present time and that the present invention is directed to an apparatus for originally surfacing new wedges or resurfacing old or used wedges which have become flattened from wear.

When it is desired to surface such a wedge the same is placed into the jig member 34

carried on the table 11 of the apparatus. The jig member serves a special use when the wedge being surfaced is an old one in view of the fact that its sides 35 are configured and arranged to provide a gauge for the thickness of the wedge. Thus when a workman places such an old wedge in the apparatus he may use the sides 35 as a "sight" by looking thereacross in order to determine whether or not there is sufficient metal remaining in the wedge to permit resurfacing. In other words, the sides 35 are of the minimum height and if the metal of the wedge protrudes above such sides, the wedge is capable of reclamation or resurfacing. On the other hand, if the wedge does not protrude above the sides 35 the workman is immediately advised that the wedge is worn beyond the practical thickness and can no longer be restored.

The operation of the surfacing or grinding apparatus itself is the same when treating new wedges or old wedges and is carried on as follows:

A wedge is first secured in the holder member by means of the securing screws or bolts 36 and the base or table 6 is adjusted vertically by means of the hand wheel 8 to bring the upper surface of the wedge to the proper height for grinding. At this point the motor 12 may be started and the table 11 together with the holder member and the wedge will be reciprocated below the grinding wheel 33. During this sidewise reciprocation of the wedge W below the wheel 33 the wedge may be moved longitudinally with respect to the wheel by means of the manually operable control 10 and as the latter movement is accomplished the master radius 40 by its engagement with the rollers 41 and 42 of the supporting structure of the motor, moves the motor 12 with the grinding wheel vertically so that the latter will follow the contour of the surface which it is desired to produce. Thus when the wedge is adjusted vertically the entire upper surface thereof is suitably ground by manipulation of the hand wheel 10.

In this connection it should be noted that the universal joints 30 in the shaft 24 and the slip connection 47 of the link 45 permit sufficient vertical movement for wedges of all normal thickness. It should also be noted that the spline connection of the shaft 24 with the gear 23 is provided in order to permit movement of the table 9 longitudinally with respect to the said shaft, this movement being that accomplished by the hand wheel 10.

The apparatus of the present invention affords very great accuracy and uniformity with respect to the curve produced and at the same time necessitates only a single adjustment to compensate for differences in the thickness of wedges being ground as well as for wear which may occur on the grinding

wheel. The full value of the above features will be appreciated more clearly from the following:

Heretofore in machines of this type, either the piece to be ground or the grinding wheels or both were mounted to swing from a fixed pivot point. When the grinding wheel of a machine of this type wears, either the radius of the curve produced changes with the result that the articles produced are not uniform or, some complicated adjusting mechanism must be provided to compensate for the change in radius. The above difficulties are overcome by the apparatus of the present invention by means of the mounting and arrangement of the wedge holder member and the grinding wheel, the same including provision for reciprocating the wedge longitudinally of the curve to be produced and for reciprocating the grinding wheel transversely of the motion of the wedge in a path perpendicular to the plane of the wedge. This arrangement results in the grinding of uniform curves regardless of the thickness of any particular wedge or the amount of wear which might accumulate on the grinding wheel.

Thus by our invention we have provided a simple, convenient and efficient apparatus for resurfacing wedges which have become unfit for further service on account of the wearing down of the upper crown surface. Furthermore our invention includes a gauge for determining whether or not used wedges are of thickness sufficient to permit re-claiming.

Our invention is still further useful in the manufacture of new wedges. At the present time the contour or crown of the wedge is originally produced in the die of a drop forge, when they are made of drop forged steel, or in a mold, when they are made of malleable iron castings. Wedges of greatly increased life may be manufactured by employing a drop forge process to produce a wedge blank which may be chilled or hardened in the crown and then ground by the apparatus of the present invention in order to produce the proper curve on the upper surface thereof. Such wedges chilled or hardened in the crown would have substantially longer life on account of their increased resistance to wear.

What we claim is:

1. A grinding device having a rotating grinding wheel adapted for grinding predetermined curved surfaces on journal box wedges, comprising a holder for the wedge, a movable support for the holder, a movable table carrying said support, means for reciprocating said support transversely of the curvature of the surface to be ground and in a plane parallel to the general plane of the grinding wheel, means for moving said table in a direction longitudinally of said curvature

and in a plane normal to the general plane of the grinding wheel, a movable mounting for the grinding wheel, a movable template having a curved surface corresponding to the curvature of the surface to be ground on the wedge, means carried by the grinding wheel mounting engaging the curved surface of the template, means connecting said template to said table for movement therewith, and means carried by a fixed part for guiding the template in such movement.

2. In a journal box wedge grinding device for grinding a surface of predetermined curvature on the wedge, the combination of a grinding wheel, a holder for the wedge, a movable support for said holder, a movable mounting for the grinding wheel, and means for raising and lowering the wheel to develop the curve, including a movable template having an upper surface of a curvature corresponding to the curvature of the surface to be ground on the wedge and having grooves in opposed edges of a curvature corresponding to the curvature of its upper surface, a roller carried by the grinding wheel mounting riding on the upper curve of the surface of the template, and other rollers carried by the grinding wheel mounting riding in the edge grooves.

In testimony whereof we have hereunto signed our names.
